APPARATUS FOR ALLOYING METALS

Daniel V. McParlin, Passaic, N. J., assignor to
 The Okonite-Callender Cable Company, Incorporated, Paterson, N. J., a corporation of
 New Jersey

Application December 5, 1936, Serial No. 114,331

1 Claim. (Cl. 266—33)

This invention relates to an improved method and apparatus for use in connection with the extrusion of metals as well as the preparation of metal alloys and their extrusion.

- 5 The device of the present invention comprises two chambers which I shall call a melting chamber and an alloying chamber. The metal such as lead is melted in the melting chamber and then passed to the alloying chamber, one charge at a time. Heretofore it has been difficult to alloy lead and lithium for extrusion, with the necessary degree of uniformity owing to the fugitive nature of the lithium, the lithium being lost to a detrimental extent during the alloying process.
- 10 Consequently one of the objects of the present invention is the provision of a process wherein the lead is melted in a melting chamber, and the molten lead then passed to an alloying chamber, one charge at a time, where the lithium is added.
- 15 As soon as the lead and lithium alloy, the alloy is discharged to the lead press.

Other objects of the present invention will be manifest from the following description and the accompanying drawing.

- 20 The drawing is a sectional elevational view of a melting pot constructed in accordance with my invention.

Referring to the drawing in detail, 2 designates the outer wall of a melting pot adapted to be heated in any desired manner. Within this pot and projecting upwardly from the bottom thereof are posts 4 for supporting a cylindrical container 6 which comprises an alloying chamber, the space between the container 6 and the wall of the melting pot constituting the melting chamber. The alloying chamber is closed except for intake and outlet ports 8 and 10 which will be described presently.

The side wall of the pot 2 is provided with flanges or brackets 12 and 14 for supporting a vertically extending rod 16, one end of which carries a hand wheel 18 and the other end a sprocket 20. Within the pot 2 another vertically extending rod 22 is mounted in brackets or flanges 24 and 26 carried by the container 6, the lower end of the rod 22 carrying a valve 28 at its lower end and a sprocket 30 at its upper end in horizontal alignment with the sprocket 20. A sprocket chain 32 passes around the sprockets 20 and 30. The brackets 16 and 24 are screw threaded to receive screw threaded portions 34 and 36 intermediate the ends of the rods 16 and 22, respectively. The valve 28, it will be noted, is in line with a valve seat 38 leading to the port 8 of the alloying chamber 2.

It will be understood that rotation of the hand wheel 18 will cause the rod 16 and the sprocket 20 to rotate which in turn, due to the sprocket chain connection, will cause the rotation of the sprocket 30 and the shaft or rod 22. As the shafts 16 and 22 are thus rotated, it will be appreciated that the valve 28 will be raised and lowered out of and into the valve seat 38 to open and close this valve.

The lead or other metal is charged into the melting chamber through the door 40 and when heated to the desired degree the valve 28 is opened as above described to permit of a single charge of the molten metal to pass into the alloying chamber 6 after which the valve is closed. When a charge of molten metal is passed into the alloying chamber 2 lithium or other metal to be alloyed with the lead is admitted to the alloying chamber in the proper proportion through the tube 42. This tube adjacent its lower end is perforated as shown at 44 for the discharge of the lithium into the mass of molten lead. The level of the charge in the alloying chamber is shown by gauge 46 which extends into the alloying chamber and is provided at its lower end with a float 48.

The charge in the alloying chamber is maintained in molten condition by means of the molten metal in the melting chamber and is stirred or agitated by means of an agitator 54, the shaft 55 of which extends through the tops of the chambers 2 and 6 and at its outer end is provided with a gear 56 which is in mesh with a pinion 58 on the shaft of a motor 60 for driving the same.

When the charge has been thoroughly mixed and alloyed the discharging valve 52 of the alloying chamber is opened to discharge the molten alloy through the outlet port 10 of the alloying chamber, this port leading to an extrusion press or other equipment.

It will be noted that the inlet valve 28 is below the level of the molten metal in the chamber 2 so that the charges of molten metal are withdrawn from below the surface of the molten mass, thereby insuring the withdrawal of metal free of oxidation.

If desired a vacuum may be drawn on the chamber 6 with both the valves 28 and 52 closed and before the admission of lead into the chamber. This evacuation of the chamber insures a clean chamber free of air or oxygen and thus preventing the oxidation of the lead when the same is admitted to the chamber. In this connection I have illustrated a vacuum line 45 hav-

ing a control valve 47 and leading to the closed chamber 6. After the chamber 6 has been evacuated the valve 28 is opened to admit a single charge of lead into the chamber 6 where it is alloyed with another metal such as lithium, as above described. To prevent any oxidation of the charge in the chamber 6 as the charge is discharged to the press past the valve 52, the vacuum in the chamber 6 is broken by closing the valve 47 in the vacuum line and admitting an inert gas to the chamber 6 from a supply tank 92. A suitable inert gas is nitrogen.

It is also to be understood that other changes may be made in the details of construction and arrangement of parts within the purview of my invention.

What I claim is:

In a device of the class described, the combina-

tion of a melting pot, a closed container within said pot spaced from the walls thereof to provide a melting chamber, a port in the wall of said chamber providing communication between said melting chamber and said closed container, a valve manually operable from the exterior of said pot for regulating the admission of molten lead through said port to said closed chamber whereby molten lead can be admitted a charge at a time to said closed chamber, means for supplying another metal to said chamber for alloying with the molten lead, means for supplying nitrogen gas to said closed chamber, means operable from the exterior of the melting pot for mixing the charges of molten lead with said other metal in said closed chamber, and means for placing the closed chamber under vacuum.

DANIEL V. McPARLIN.
